CLAIM

The ornamental design for a vaporizer cartridge, as shown and described.

DESCRIPTION

FIG. 1 is a top, front, and right side perspective view of a vaporizer cartridge of our design;

FIG. 2 is a bottom, rear, and left side perspective view thereof;

FIG. 3 is a top, front, and right side perspective view thereof;

FIG. 4 is a bottom, rear, and left side perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines illustrate portions of the vaporizer cartridge that form no part of the claimed design.

1 Claim, 8 Drawing Sheets
